Filed Oct. 12, 1960, Ser. No. 108,964

18 Claims. (Cl. 254—167)

This invention relates to a winch hoist and more particularly to apparatus arranged to exert forces and lift loads through the medium of a cable or chain.

In the construction of winch hoists making use of the pawl and ratchet principle, devices made in the past have provided not only for lifting a load upwardly but also for rearranging the pawls so that the load may be lowered. While it is a relatively simple matter to arrange for moving the load upwardly, either one tooth at a time or a plurality of teeth at one time, the lowering operation for more than one tooth at a time has been somewhat more difficult. It has been common practice to manufacture hoists of this kind capable of lowering the load by fixed plurality of teeth at any given time, usually the same number of teeth as in lifting. This large lowering increment makes it difficult to adjust the load or to lower it to a fixed position. With very heavy loads it is also somewhat dangerous to lower at a rapid rate. These and other difficulties experienced with the prior art devices have been obviated in a novel manner by the present invention.

It is, therefore, an outstanding object of the invention to provide a hoist which may be lowered in increments different from the size of the increments by which it is raised.

Another object of this invention is the provision of a hoist which may be lowered at a small increment of movement or selectively in multiples of that increment.

A further object of the present invention is the provision of a winch hoist using a toothed ratchet and pawl in which the load may be lowered in selected sub-divisions of the number of teeth by which it may be raised.

It is another object of the instant invention to provide a winch-type hoist using a toothed ratchet in which the load may be lowered either one tooth at a time or in multiples of one tooth at a time.

It is a further object of the invention to provide a winch hoist in which a load may be lowered in small increments or in large increments, the increments being selectively adjustable.

A still further object of the invention is the provision of a winch hoist using a ratchet and double pawls in which most of the apparatus is compact and there is little danger of the operator being hurt by the mechanism.

It is a still further object of the present invention to provide a winch hoist which is compact and clean in external appearance, which is simple in construction, which may be readily manufactured from easily obtained materials, which is relatively free of maintenance problems and has an open construction which may be readily inspected for clogging by an accumulation of dirt and which can be easily cleaned, if dirty, by use of simple cleaning materials.

A further object of this invention is the provision of a winch hoist having ratchet teeth, wherein lowering may take place in increments of more than one tooth at a time.

Another object of the invention is the provision of a winch hoist of open construction that may be easily inspected for wear without dis-assembly and, should repair or replacement of parts be necessary, may be disassembled and assembled with simple tools.

With these and other objects in view, as will be apparent to those skilled in the art, the invention resides in the combination of parts set forth in the specification and covered by the claims appended hereto.

2

The character of the invention, however, may be best understood by reference to one of its structural forms, as illustrated by the accompanying drawings in which:

FIG. 1 is a perspective view of a winch hoist embodying the principles of the present invention,

FIG. 2 is a perspective exploded view of the hoist,

FIG. 3 is a sectional view of a portion of the invention taken along the line III—III of FIG. 1, and

FIGS. 4, 5, 6, 7, 8, 9, and 10 are schematic views of the important elements of the invention showing them in operative relationship.

Referring first to FIG. 1, wherein are best shown the general features of the invention, the hoist, indicated by the numeral 10, consists of a main frame 11, through which extends a main shaft 12 on which are mounted an actuating pawl cam 13, a locking pawl cam 14, an actuating handle 15, and a selector disk 16. Also mounted on the frame is a locking pawl 17, while an actuating pawl 18 is shown in FIG. 2 as mounted on the actuating handle. Swiveled to the top of the main frame 11 is a hook 19 and extending through the frame is a flexible load-carrying member such as the link chain 21 having a hook 22 at its lower end.

Referring to FIG. 2, which best shows the details of construction of the individual elements of the invention, the main frame 11 is shown as having two sides 23 and 24 joined at their upper end by a web 25 through which the shank of the hook 19 extends. One edge of the side 23 is formed with an apertured boss 25 for permitting variations in the hoisting rig. The outer surface of the side 24 is provided with a cylindrical boss 26 having an axial bore 27 carrying a bronze bushing 28. The side 23 of the main frame 11 is also provided with a bore and bronze bushing, but of much smaller size. A web 29 extends between the side 23 and the side 24 in the upper part of the housing and overlies an imaginary cylinder joining the two bores. The web is somewhat semi-circular in cross sectional shape and faces downwardly to act as a shield for the elements which extend between the bores. At its upper corner the side 24 is provided with a bore 31 and a similar bore in the side 23 is aligned with it to receive a shaft 32 on which the locking pawl 17 is mounted.

In the description of the elements it will be assumed that the hoist is in the position shown in FIG. 1 with the hook at the upper portion. It will be understood that, although the hoist can be used in other positions, the expressions "horizontal," "vertical," "up," and "down," and like expressions will be used to indicate those relationships with the hoist suspended from the hook 19 and with the load pulling downwardly on the hook 22. Mounted in the side 24 are two pins 33 and 34, the former extending from the housing at the horizontal level of the axis of the bore 27 and slightly spaced outwardly from the outer surface of the boss 26. The pin 34 is mounted about the same distance from the boss 26 but is located considerably above the horizontal level of the axis of the bore 27. The rearward end of the shaft 32 is provided with a groove 35 in which may be snapped a lock ring 36 which, in assembly, presses against the outer surface of the side 23 of the main frame. The shaft 32 extends a considerable distance from the outer surface of the side 24 and on this extending end of the shaft is mounted a washer 37 as well as the locking pawl 17. This end of the shaft 32 is also provided with a groove 38 in which is snapped a lock ring 39.

In the shaft and its associated elements including the pawl 17 mounted in place the pawl is free to turn about the axis of the shaft. Mounted on the inner surface of the pawl which, as can be seen, is spaced away from the surface of the side 24 by the washer 37 is mounted a spring-loaded cam follower 41 which is mounted in a sheet metal housing 42 mounted on the back of the pawl 17 and con-

taining a coil spring 43. The cam follower 41 is a small wheel-like element which is retained within the housing by means of a slot and shaft arrangement (not shown). The upper end of the spring is locked in place by a lug 44 extending across the top of the housing. A finger 45 extends from the top of the housing 42 and into the lower end of the coil spring 46 which is suspended from the end of a finger 47 which extends outwardly from a plate 48 fastened to the upper rear edges of the sides 23 and 24 of the main frame. The pawl 17 is somewhat elongated and is provided at one end with an aperture 49 by which it is mounted on the shaft 32 and at the other end by a tooth 51 which is formed by two flat surfaces extending at an angle of approximately 45° to one another. Mounted on the boss 26 and pressed against the outer surface of the side 24 is the actuating pawl cam 13 which is formed of relatively thin steel plate and which is provided with a central aperture 52. This aperture has a vertical dimension the same as the outside surfaces of the boss 26, but its horizontal dimension is considerably larger so that the cam 13 is capable of considerable movement in a horizontal direction across the face of the cam, but not vertical movement. In addition, the cam is provided with an elongated slot 53 in which resides the pin 34 and an elongated notch 54 extending inwardly from the edge of the aperture 52 and in which the pin 33 normally resides. The cooperation of the pins 33 and 34 with the notch 54 and the slot 53, respectively, restricts the cam to horizontal motion across the face of the side 24 of the main frame. Extending outwardly from the cam in the area just above the notch 54 is a cam follower 55 which consists of a rotatable cylinder mounted on a pin. The outer periphery of the cam 13 has a flat horizontal edge 56 at the upper portion and a flat horizontal edge 57 at the lower portion joined on the back side by a generally circular edge 58. The remainder of the edge of the cam occupied by a raised circular edge 59 and a lower edge 61 both of which are generally concentric with the axis of the bore 27 of the boss 26 and which are joined by a fairly abrupt transition surface 62. The locking pawl cam 14 is also made of thin steel plate and is provided with a central aperture 63 which is perfectly circular and which fits snugly around the outer surface of the boss 26. The outer edge of this cam is provided with a high surface 64, an intermediate surface 65, and a low surface 66. The intermediate surface 65 and the low surface 66 are joined by smooth transition surface 67. The intermediate surface 65 and the high surface 64, however, are joined by an abrupt radial surface 68 extending inwardly from the surface 64 and a curved concave surface 69 having approximately the same curvature as the cam follower 55. The proportion of the periphery of the cam occupied by the various surfaces will be explained in connection with the operation of the device. The end of the surface 64 away from the radial surface 68 is occupied by a finger 71 in which is formed an aperture 72. On the other side of the finger 71 the outer edge of the cam is formed with a continuation of the high surface 64 which extends a short distance beyond the finger and terminates in a transition surface 73 by which it is joined to the low surface 66, the transition surface having a somewhat S-shaped configuration providing a point at the outermost end and a concave inner portion which joins with the low surface 66.

The main shaft 12 is provided at one end with a reduced portion 74 intended to rotate in the bushing in the aperture in the side 23 which corresponds to the bore 27 of the side 24. This bushing and bore, of course, are much smaller than those in the side 24. Externally, a washer 75 and a bolt 76 (or similar fastener) serve to lock the shaft in the main housing by means of a threaded hole (not shown) in the end of the shaft. The other end of the shaft is provided with a ratchet wheel 77, which, in the preferred embodiment, is integral with the rest of the shaft. All of the shaft parts are made in the preferred embodiment of a single forging. The shaft on either side

of the ratchet wheel is quite large and fits snugly within the bushing 28 in the boss 26. The immediate portion of the shaft is provided with a chain formation 78 of the usual type which will grasp a chain tightly during the rotation of the shaft. At its outer end the shaft is provided with a groove 79 in which a snap ring 81 is intended to be placed upon assembly of all the elements.

The actuating handle 15 has in its inner end a ring 83 having a bore 84 of such a size as to slide smoothly over the outer end of the shaft 12. The outer surface of the ring is provided with notches 85 (for a purpose to be described more fully hereinafter). Fastened to the handle adjacent the ring 83 is a pair of retaining plates 86 and 87 which extend parallel to one another away from the actuating handle 15 and on which is adapted to be fastened a cover member 88. Fastened to one edge of the cover member 88 is a bottom 89. The retaining plates 86 and 87, the cover member 88, and the bottom 89 fit together to form a box-like structure for containing the actuating pawl 18, there being an open side facing the ring 83. The bore 91 extends through the cover member 88 at the end opposite the bottom 89 and this bore is intended to carry a shaft 92. One end of the shaft is provided with a groove 93 adapted to receive a snap ring 94 and at the other end is provided with a groove 95 to receive a snap ring 96. Mounted on the shaft are washers 97 and 98 followed by the actuating pawl 18 which is provided with a bore 99 whereby it may be mounted on the shaft 92 for free rotation.

A more detailed description of the actuating pawl 18 may be understood by referring to FIG. 3 which is a section through the retaining plates 86 and 87 as well as the bottom 89. Fastened to the pawl 18 in the side facing the cover member 88 is a spring-biased cam follower 101 which is generally cylindrical and which is provided with an axial shaft 102 slidably received in a slot 103 formed in a sheet metal housing 104 fastened to the pawl 18. Enclosed within the housing and pressing against the cam follower 101 is a coil spring 105. A finger 106 extends from the housing toward the bottom 89 and a peg 107 is mounted in the bottom 89 in opposition to the finger; a coil spring 108 extends between the finger and the peg and tends to force the pawl in a direction away from the bottom 89 and toward the ratchet wheel 77. In this figure it can be seen that the teeth in the ratchet wheel 77 are formed with smooth back surfaces 109 and the forward edge 111 of each of the ratchet teeth is formed at a slight negative angle; that is to say, the surface extends somewhat inwardly of a radial line so that, when the point 112 of the cam 18 resides against a tooth with the forward edge 113 of the point pressing against the forward edge 111 of the tooth, the pawl is not free to swing away from the ratchet wheel, particularly when the ratchet wheel is forced against the pawl so that the surfaces 113 and 111 are held in contact with one another. To release the pawl so that it may move away from the ratchet wheel, it is necessary to move the ratchet wheel slightly so that the surfaces may come apart and so that the surface 113 may slide free of the ratchet tooth.

The selector disk 16 is provided with a central aperture 114 which slides over the shaft 12 at its outer end. It is also provided with an axial flange 115 extending around its outer periphery, this flange having an inner surface adapted to fit tightly against the outer periphery of the ring 83. The outer surface of the flange 115 is provided with smooth notches 116 to permit it to be readily grasped and turned by the operator. Located in the flange is a spring-biased ball detent 117, the ball extending inwardly of the inner surface of the flange and coming into contact with the notches 85 in the ring 83. The ball and its spring are retained in place by a well-known manner. A finger lug 118 is secured to the flat face of the selector disk at one side of the aperture 114, while a similar lug 119 is fastened to the other side diametrically opposite. The lug 119, however, is provided with a finger 121 which

extends along the outer surface of the flange 115 in an axial direction and carries at its extreme end a pin 122 which extends axially also; upon assembly of the parts, this pin resides in the aperture 72 of the finger 71.

The assembly of the apparatus will be clear from the above description and from the drawings, particularly FIG. 2. The main shaft 12 is mounted within the main frame 11 with the chain formation 78 residing between the sides 23 and 24 and under the web 29. The chain is threaded through this and is held against slippage. In other words, the chain formation 78 is such that, if the main shaft is held against rotation, the chain cannot slip through. The locking pawl 17 is pivotally mounted on the main frame with its spring-biased cam follower 41 extending slightly below its periphery. The actuating pawl cam 13 is, as has been described, capable of only slight sliding motion in a horizontal direction. The locking pawl cam 14, however, is capable of being completely rotated about the outer surface of the bushing 26. The actuating pawl 18 rotates about its shaft 92 and carries its spring-biased cam follower 101 extending slightly above its upper surface. The spring 108, of course, keeps the whole pawl 18 pressed inwardly toward the ratchet wheel 77, and a similar function is provided by the spring 46 in connection with the pawl 17. The locking pawl cam 14 and the selector disk 16 are locked together by the finger 122 so that the movement of the selector disk causes a corresponding movement of the cam 14 relative to the handle 15.

The operation of the invention will now be readily understood. In this connection, reference is made to FIGS. 4 through 10 of the drawings which show somewhat schematically the arrangement of the parts during operation. Assume that the winch hoist 10 is suspended by the hook 19 from a ceiling joist or some overhead supporting member, and a load is carried by the hook 22 on the end of the chain 21; let us also assume that it is desired to lift the load by rotating the main shaft 12 and thus pass the chain 22 through the space between the chain configuration 78 and the web 29 of the main frame. The selector disk is rotated counter-clockwise until it can be turned no longer. Since turning the selector disk also moves the cam 14, eventually the transition surface 73 will strike the cam follower 55 on the cam 13. Since the surface 73 is formed in a concave manner, it will force the cam follower 55 to the right in FIG. 4 (if it has not already been moved to that position by pressure of the actuating pawl) and carry the entire cam in that direction, it being capable only of horizontal motion because of the engagement of the slots 53 and notch 54 with the pins 34 and 33. In FIG. 4 the left hand position of the cam 13 is shown in dotted lines and indicated by the reference numeral 123, whereas the solid line position indicated by the reference numeral 13 is the position where it now finds itself. In that position the actuating pawl 18 rests against the outside edge of the teeth of the ratchet wheel 77, since its cam follower 101 does not touch the raised surface 59 of the cam 13. Incidentally, the turning of the selector disk 16 to this extreme position results in a situation wherein the cam follower 41 of the locking pawl 17 does not engage its cam 14 either. The point of the pawl 17 is pressed by the spring 46 into engagement with the teeth of the ratchet wheel 77. In this case it is shown that the point engages a tooth of the ratchet. The pawl 18, of course, is pressed by the spring 108 toward the ratchet wheel and, as the handle 15 is moved upwardly, the pawl 18 rides up over each tooth of the ratchet wheel and falls into each of the valleys. As soon as the actuating arm 15 reaches the uppermost position desired, the operator starts its downward movement. It should be noted in connection with the upward movement that, even though the cam 14 moves along with the arm 15, because of the engagement of the spring-pressed ball detent 117 with the extreme notch 85 on the ring 83, no

part of the cam extends far enough away from the shaft to contact the cam follower 41 and effect the placement of the locking pawl 17. The locking pawl, incidentally, is locked against a tooth because of the aforementioned negative angle on the face of the tooth and the point of the pawl which is jammed against it, due to the load attempting to rotate the ratchet wheel in a clockwise direction. When the operator starts the downstroke of the handle 15, the actuating pawl 18 immediately hits against the next tooth, since its spring 108 biases it in this direction and the position of the cam 13 is so far away that it does not affect the pawl 18. As soon as the actuating pawl 18 strikes the face of the tooth, further movement of the arm 15 causes rotation of the ratchet wheel 77. It also removes the force between the locking pawl 17 and the forward face of its tooth, so that it is free to swing away from the surface of the ratchet wheel. Its spring 46, of course, presses it toward the ratchet wheel so that it climbs over each tooth and falls into each valley, but does not prevent counter-clockwise rotation of the ratchet wheel. This means, also, that, when the operator reverses the direction of the handle 15 and starts it upward again, the next tooth of the ratchet wheel will automatically be engaged by the locking pawl 17. In other words, the load is held first by the locking pawl and then by the actuating pawl, the two pawls alternating and causing the ratchet wheel 77 and the main shaft 12 to rotate in a counter-clockwise direction. This moves the chain through the main frame and causes the load to rise.

When it is desired to lower the load, the handle 15 is held in a fixed position and the selector disk 16 is rotated counter-clockwise until one of the numbers inscribed on it comes opposite an indicator mark on the handle. The number selected will determine the number of teeth which will be released at each stroke of the handle in lowering the load. FIGS. 6, 7, 8, and 9 show lowering taking place at the rate of a single tooth per stroke. In FIG. 6 the operator is starting the upward stroke of the handle 15. The actuating pawl 18 engages a tooth of the ratchet wheel, while the locking pawl 17 does not do so. This is because the cam follower 41 resides on the high surface 64 of the cam 14. As the handle moves upwardly, however, it soon reaches the position shown in FIG. 7 and the cam follower 41 has fallen past the radial surface 68 extending between the high surface 64 and the intermediate surface 65 of the cam 14. This means that the locking pawl 17 is free to move toward the ratchet wheel 77 and does so, engaging the forward edge of the next tooth to arrive after the cam follower 41 leaves the high surface 64. The cam follower 101 of the pawl 18 has passed upwardly onto the high surface 59 of the cam 13, thus causing the pawl 18 to remain outside of the outer circle of the ratchet wheel 77. No matter how much further the arm 15 is raised after this point in the cycle, the ratchet wheel will not be moved nor will the condition of the cam be changed. The locking cam will be holding the ratchet wheel and the load, while the cam follower 101 will merely be sliding along the surface 59 of the cam 13 with the pawl 18 out of engagement with the ratchet wheel. The operator then reverses the movement and brings the handle 15 into the position shown in FIG. 8. Close to the bottom of the downstroke, the cam follower 101 will leave the surface 59 of the cam 13, move down the transition surface 62, and will then lie closely adjacent the lower surface 61, but will not touch it. In any case, this movement causes the point of the pawl to press against the outer surface of the ratchet wheel under the influence of the spring 108 so that, unless a forward edge of the tooth is immediately present, the pawl 18 merely slides over the outer ends of the teeth. It will be remembered that the locking pawl 17 has been locked against a tooth of the ratchet wheel 77 because of the negative angle of their surfaces. It cannot leave until

the pressure between the tooth and the point has been relieved. In FIG. 9 the operator continues the down-stroke and the pawl 18 makes engagement with the front edge of a tooth; the load is taken over by the actuating arm and the actuating pawl 18; this relieves the locking pawl 17 of its load. When this occurs, the forces between the point and the forward edge of the tooth are relieved and a slight movement of the ratchet wheel is sufficient to release the pawl 17. Incidentally, it will be understood that the pawl remains in engagement with a given tooth despite movement of its cam follower over high portions of the cam, so long as the pawl carries the load. The release of the pawl from the tooth takes place only because the spring 105 in the cam follower has a greater spring constant than the main pawl spring 103 and can on occasion over-ride it. At this time the cam 14 has rotated far enough so that the cam follower 41 is residing on the high portion 64 of the cam 14 so that the moment the pawl 17 is released from the ratchet tooth, the spring pressure due to the cam follower on the cam surface 64 will cause the pawl 17 to move away from the ratchet. At that point the apparatus is in the condition shown in FIG. 9 and the operator is free to begin another upward stroke of the handle. It should be noted that the movement of the selector disk in the manner described has caused the surface 65 of the cam 14 to press against the cam follower 55 on the cam 13 and has caused the cam 13 to move completely over to the left and stay there during the entire lowering stroke, because of the extreme length of the surface 65. That is why it is able to control the movement of the actuating pawl 18 during the lowering cycle.

It will be understood that movement of the selector disk 16 to bring numerals 2, 3, and 4 into alignment with a marker on the handle 15 will cause the cam 14 to lie in various positions relative to the handle and to the actuating pawl. For instance, in FIG. 10 the selector disk has been moved to the numeral 4. This means that the end radial surface 68 of the cam 14 resides much further around the ratchet wheel than it does in, say, FIG. 6. This means that the handle is rotated a much greater distance upwardly before the cam follower 41 falls off the edge of the surface 64 to permit the pawl 17 to engage the next tooth; otherwise the operations are the same. There are two or three teeth in the letdown cycle, when the cam is positioned at points between those shown in FIG. 6 and FIG. 10. It will be understood in connection with FIG. 10 that the raised edge 59 of the cam 13 is located in such a position that the cam follower 101 of the pawl 18 does not strike it until the cam 14 has been moved a sufficient distance to release the pawl 17 and permit it to engage the ratchet wheel 77. In other words, the angle through which the arm 15 must travel before the pawl 18 is released from the ratchet wheel is set for the largest number of teeth which are to be used in lowering the hoist. In the case of the preferred embodiment, this would be four teeth. The raised edge 59 of the cam 13 is located in a fixed radial position, since the cam cannot turn. The cam follower 101 always drops off the edge 59 at a point midway between ratchet teeth 77, because of the engagement of the pawl 17 with its tooth. This places the pawl 18 always in the position of engaging the last tooth at the bottom of the lowering stroke.

It can be seen, then, from the above description that with the present winch hoist it is possible to raise a load four teeth at a time and to lower it at any selected rate from one tooth to four teeth per stroke. It will be understood that a rope, roller chain, metallic cable, or the like may be used in place of the link chain 21. It should also be noted that the selector disk 16 can be rotated either fully clockwise to obtain raising and fully counter-clockwise to obtain maximum lowering; this can be done in the dark or, at least, without looking and there is no

danger of error in direction. In other words, there is a complete stop at each end of the cycle of rotation and it is not possible to reverse the direction of load movement by continuing rotation past one end. One of the desirable features of this hoist is the fact that the chain, cable or rope may be freely released in either direction when it is entirely free of load. This is accomplished by turning the selector disk to 4-tooth lowering and setting the handle 15 within the range from 30 degrees above to 30 degrees below horizontal. In this position and without a load on either pawl, the spring-loaded cam followers will force both pawls out of engagement with the ratchet and will provide free release in both directions. This function is accomplished automatically and does not require that the operator hold one pawl down manually or place his fingers in the mechanism in any way. Free release is important when taking up slack when preparing to hook the chain to a load; the slightest load, however, causes one of the pawls 17 or 18 to lock securely.

It is obvious that minor changes may be made in the form and construction of the invention without departing from the material spirit thereof. It is not, however, desired to confine the invention to the exact form herein shown and described, but it is desired to include all such as properly come within the scope claimed.

The invention having been thus described, what is claimed as new and desired to secure by Letters Patent is:

1. A winch hoist, comprising a main frame, a main shaft rotatably mounted on the frame, a ratchet wheel fixed to the main shaft, an actuating handle pivotally mounted on the main shaft, a locking pawl pivotally mounted on the main frame in position to engage and hold the ratchet wheel, an actuating pawl pivotally mounted on the actuating handle in position to engage and rotate the ratchet wheel, and cam means having a first portion adjustably mounted and movable on and movable with the ratchet wheel for engagement with the locking pawl and a second portion mounted on the frame for engagement with the actuating pawl, the cam means causing the ratchet wheel to be automatically rotated in equal increments selected from a plurality of substantially different increments in lowering a load.

2. A winch hoist, comprising a main frame, a main shaft rotatably mounted on the frame, a ratchet wheel fixed to the main shaft, an actuating handle pivotally mounted on the main shaft, a locking pawl pivotally mounted on the main frame in position to engage and hold the ratchet wheel, an actuating pawl pivotally mounted on the actuating handle in position to engage and rotate the ratchet wheel, cam means having a first portion adjustably mounted on and movable with the ratchet wheel for engagement with the locking pawl and having a second portion mounted on the frame for engagement with the actuating pawl, the cam means causing the ratchet wheel to be automatically rotated in equal increments selected from a plurality of substantially different increments in lowering a load, and means for moving the cam relative to the wheel to determine the size of the said increments.

3. A winch hoist, comprising a main frame, a main shaft rotatably mounted on the frame, a ratchet wheel fixed to the main shaft, an actuating handle pivotally mounted on the main shaft, a locking pawl pivotally mounted on the main frame in position to engage and hold the ratchet wheel, an actuating pawl pivotally mounted on the actuating handle in position to engage and rotate the ratchet wheel, both pawls being spring-biased toward engagement with the ratchet wheel, and cam means having a first portion adjustably mounted on and movable with the ratchet wheel for engagement with the locking pawl and having a second portion mounted on the frame for engagement with the actuating pawl, the cam means causing the ratchet wheel to be automatically rotated in equal increments selected from a plurality of substantially different increments in lowering a load.

mounted on the main shaft, a locking pawl pivotally mounted on the main frame in position to engage and hold the ratchet wheel, an actuating pawl pivotally mounted on the actuating handle in position to engage and rotate the ratchet wheel, each pawl having a cam follower mounted thereon with a spring interposed between each pawl and its cam follower, a cam engaging the cam follower of the locking pawl on occasion, a cam engaging the cam follower of the actuating pawl on occasion, these cams causing the ratchet wheel to be rotated automatically in selected increments in lowering a load, and means for adjusting the cams relative to the ratchet wheel to determine the size of the said increments.

15. A winch hoist, comprising a main frame, a main shaft rotatably mounted on the frame, a ratchet wheel fixed to the main shaft, an actuating handle pivotally mounted on the main shaft, a locking pawl pivotally mounted on the main frame in position to engage and hold the ratchet wheel, an actuating pawl pivotally mounted on the actuating handle in position to engage and rotate the ratchet wheel, both pawls being spring-biased toward engagement with the ratchet wheel, each pawl having a cam follower mounted thereon with a spring interposed between each pawl and its cam follower, a cam engaging the cam follower of the locking pawl on occasion, a cam engaging the cam follower of the actuating pawl on occasion, these cams causing the ratchet wheel to be rotated automatically in selected increments in lowering a load, and means for adjusting the cam relative to the ratchet wheel to determine the size of the said increments.

16. A winch hoist, comprising a main frame, a main shaft rotatably mounted on the frame, a ratchet wheel fixed to the main shaft, the ratchet wheel having teeth with forward edges with negative rake, an actuating handle pivotally mounted on the main shaft for movement through an upstroke and a downstroke, a locking pawl pivotally mounted on the main frame in position to engage and hold the ratchet wheel as the handle moves at the end of an upstroke, an actuating pawl pivotally mounted on the actuating handle in position to engage and rotate the ratchet wheel as the handle moves at the end of a downstroke, both pawls being spring-biased toward engagement with the ratchet wheel, each pawl having a point adapted to engage the forward edges of the teeth of the ratchet wheel and having a cam follower mounted thereon with a spring interposed between each pawl and its cam follower, an actuating pawl cam mounted on the main frame so as to be capable only of slight linear sliding motion thereacross and having a high edge which contacts the cam follower of the actuating pawl and renders the actuating pawl ineffective to engage the ratchet wheel when the actuating handle is moved to the end of an upstroke while lowering a load, a locking pawl cam mounted on the main frame for rotation and being fastened to the actuating handle for rotation therewith, the locking pawl cam having a high surface which engages the cam follower of the locking pawl to render the locking pawl ineffective to engage the ratchet wheel during the beginning of an upstroke of the actuating handle while lowering a load, means adapted to connect

the two cams while lifting a load to render both pawl cams ineffective to contact either cam follower, the cams causing the ratchet wheel to be rotated automatically in selected increments in lowering a load, and means for adjusting the angular relationship between the handle and the locking pawl cam to select the size of the said increments.

17. A winch hoist, comprising a main frame, a main shaft rotatably mounted on the frame, a ratchet wheel rotatable with the main shaft, an actuating handle mounted for pivotal action, a spring-biased locking pawl pivotally mounted in position to engage and hold the ratchet wheel, a spring-biased actuating pawl pivotally mounted on the actuating handle in position to engage and rotate the ratchet wheel, each pawl having a cam follower mounted thereon with a spring located between each pawl and its cam follower, a cam locked for rotation with the handle and engaging the cam follower of the locking pawl on occasion, a cam engaging the cam follower of the actuating pawl on occasion, the cams causing the ratchet wheel to be rotated automatically in selected increments in lowering the load, and means for adjusting the angular relationship between the handle and the locking pawl cam for selecting the size of the said increments.

18. A winch hoist, comprising a main frame, a main shaft rotatably mounted on the frame, a ratchet wheel fixed on the main shaft, an actuating handle pivotally mounted on the main shaft, a locking pawl pivotally mounted on the main frame in position to engage and hold the ratchet wheel, an actuating pawl pivotally mounted on the actuating handle in position to engage and rotate the ratchet wheel, means alternately releasing the pawls to rotate the ratchet wheel in raising the load so that a plurality of teeth can pass a given point, and cam means having a first portion adjustably mounted on and movable with the ratchet wheel for engagement with the locking pawl and having a second portion mounted on the frame for engagement with the actuating pawl, the cam means causing the ratchet wheel to be automatically rotated in equal increments selected from a plurality of substantially different increments in lowering a load, the first portion of the cam means being adjustable relative to the ratchet wheel so that a portion of each pawl engages the cam means and the pawls operate alternately to engage the ratchet wheel in lowering a load in such a manner that a number of teeth in the range from one to the said plurality of teeth pass a given point.
